UNITED STATES PATENT OFFICE.

EDMUND W. ELLINGTON, OF OWENSBORO, KENTUCKY, ASSIGNOR OF ONE-HALF TO RICHARD N. ELLIOTT, OF OWENSBORO, KENTUCKY;

MOLD FOR MAKING COFFIN-BOXES.

No. 926,554.

Specification of Letters Patent. Patented June 29, 1909.

Application filed May 2, 1908. Serial No. 430,553.

To all whom it may concern:

Be it known that I, EDMUND W. ELLINGTON, a citizen of the United States of America, residing at Owensboro, in the county of Daviess and State of Kentucky, have invented new and useful Improvements in Molds for Making Coffin-Boxes, of which the following is a specification.

This invention relates to molds for making concrete coffin boxes, and one of the principal objects of the same is to provide a simple stamped-up sheet metal mold for molding concrete coffin boxes in which a series of said molds can be used one within the other to form a series or number of coffin boxes at the same time.

Another object of the invention is to provide means for holding the various mold members at the required distance apart during the molding operation.

These and other objects may be attained by means of the construction illustrated in the accompanying drawing, in which,—

Figure 1 is a longitudinal section taken through a plurality of molds and showing the coffin boxes molded before they are removed therefrom. Fig. 2 is a bottom plan view of the coffin lid. Fig. 3 is a transverse sectional view taken centrally through Fig. 1. Fig. 4 is a transverse section taken through the mold for the coffin lid and showing a concrete lid within the mold.

Referring to the drawing for a more specific description of my invention, the numbers 1, 2 and 3 designate the three separate molds for molding two coffin boxes. It will be understood that these coffins are of different sizes, and hence to form two coffins three molds may be used. These molds may be conveniently made of sheet metal stamped up to the required shape and provided with suitable offsets 4 of different sizes, said offsets forming a groove near the opposite ends of the bottom of the coffin so that the lowering strap may be removed after the coffin has been lowered into the grave. The upper edges of the molds 1, 2 and 3 are substantially coincident or flush so that a trowel or other slicking tool may be used for scraping off the superfluous concrete.

To hold the molds in their proper relative positions during the molding operation three or more ears 5 project upwardly from the

molds at the required distance apart at the upper edge of said molds, and formed in these ears are keyhole slots 6. A holding rod 7 provided with a series of projections 8 upon its upper side has a handle 9 at one end, said handle being turned down upon the opposite side of the rod from the projections 8. The rods 7 are inserted in the ears 5 by bringing the projections 8 into coincidence with the smaller portions of the keyhole slot 6 and by pushing said rods through the slots and by turning the handle 9 down, the various molds 10 are locked at the required distances apart, as will be understood.

For molding the lid or cover of the coffin a plain rectangular mold with rounded corners is provided, as shown in Fig. 4. This mold 10 is provided with projections or offsets 11 and a marginal flange 12. The concrete 13 forming the lid is poured into the mold and is smoothed off at the top. The groove formed between the projections 11 fits upon the upper edge of the coffin, and thus holds it from moving from side to side.

From the foregoing it will be obvious that my invention permits the molding of a number of coffins at the same time and renders the process easy, rapid and economical.

Having thus described the invention, what is claimed as new, is:—

The herein described mold for concrete coffins comprising a plurality of mold sections of graduated sizes adapted to be placed one within another and spaced apart for the concrete material for molding the coffins, each of said sections being provided with aligned ears upon the upper edges thereof, said ears each having a keyhole slot arranged in alinement, and a holding bar comprising a rod provided with projections upon one side thereof for engaging said keyhole slots to suspend said molding sections the required distances apart for molding the coffins between them, said holding bar being provided with a handle for rotating and withdrawing the same from the slots.

In testimony whereof I affix my signature in presence of two witnesses.

EDMUND W. ELLINGTON.
